DESIGN FOR AN APRON

Ada Quinn, Ogden, Utah

Application April 27, 1934, Serial No. 51,558

Term of patent 3½ years

To all whom it may concern:

Be it known that I, Ada Quinn, a citizen of the United States, residing at Ogden, in the county of Weber and State of Utah, have invented a new, original, and ornamental Design for an Apron, of which the following is a specification, reference being had to the accompanying drawing, forming part thereof.

The figure is a plan view of an apron, showing my new design.

The strings at the neck and waist-line of the apron extend to the length essential to adapt the apron to the size of the wearer.

I claim:

The ornamental design for an apron as shown and described.

ADA QUINN.
